EDWIN LEHR, OF EDGEWOOD PARK, PENNSYLVANIA, ASSIGNOR TO WESTINGHOUSE ELECTRIC & MANUFACTURING COMPANY, A CORPORATION OF PENNSYLVANIA.

PRIMARY RELAY FOR INDUCTION REGULATORS.

Application filed September 8, 1924. Serial No. 736,426.

My invention relates to regulator systems and has special relation to electric relays utilized for regulating the voltage, or any other electrical quantity, of alternating-current circuits.

In a motor driven feeder regulator of the induction type, the operation of the motor is controlled by means of a relay commonly designated as a contact-making voltmeter. Variations in the voltage on the circuit with which the regulator is associated causes the voltmeter to close the one or the other of two motor circuits, and thereby to so operate the motor as to move the induction regulator in the one or the other direction in order to increase or decrease the voltage, as required.

It has been customary to control an induction regulator by means of a contact-making voltmeter controlling a floating contact device that co-operates with two fixed contact members. The gap between the contact members determines the permissible voltage variation before the regulator will be operated in either direction. With the control magnet of the contact-making voltmeter undamped, the regulator operates freely to correct the slight voltage changes of short duration. Such a regulator also has a tendency to hunt or to carry the correction beyond the desired normal value in either direction.

One object of my invention is to provide a contact-making relay that is sensitive to voltage changes in the circuit to be regulated to govern the operation of the regulator.

Another object of my invention is to provide a relay of the above-indicated character that shall be sensitive to slight variations in voltage changes, should the variations in voltage be maintained for a predetermined time, but shall not be sensitive to temporary slight changes in voltage values.

Another object of my invention is to provide a relay of the above-indicated character that will control the regulator to prevent hunting action.

My invention will be better understood by reference to the accompanying drawing in which the single figure is a diagrammatic view of the apparatus and arrangement thereof used in an embodiment of my invention.

Referring to the drawing, an induction

coil 4 being connected in parallel with the circuit and the secondary coil 5 being connected in series with the circuit. An electric motor 6 is provided to actuate the coil 5 relatively to the coil 4, in accordance with the correction required to maintain a constant voltage in the circuit 2-3.

A relay 7, or contact-making voltmeter, is provided to control the operation of the motor 6. The relay is operated by means of an electro-magnet provided with a coil 8 that is energized from the transformer 9, connected across the circuit 2-3. The core 11 of the electromagnet operates a lever 12 pivoted at 13 and carrying a pair of contact members 14 and 15. Co-operating with the contact members 14 and 15 are auxiliary members 16 and 17 mounted on the bell-crank lever 18, pivoted at the point 19. A pair of flexible connecting members, such as helical springs 21 and 22 are provided, one of these members 21 connecting the levers 12 and 18, and the other connecting the lever 18 to a fixed support 23. To the lever 18 is attached a device for retarding the motion thereof, such as a dashpot 24.

The contact members of the primary relay 7 are connected to selectively energize operating coils 25 or 26 of the secondary relay 27. The operating coil 25, when energized, operates a relay to close the contact members 28 and the contact members 29, causing the motor 6 to operate in one direction. The operating coil 26, when energized, operates a relay to close contact members 31 and 32 to operate the motor 6 in the opposite direction. As will be noted by an inspection of the drawing, the motor 6 is illustrated as a three-phase motor energized from a separate three-phase source of supply, the motor leads 33, 34 and 35 being connected to the alternating-current source 36, 37 and 38 in a particular phase relation, in accordance with the energization of the relay coils 25 or 26 of the secondary relay 27.

The operation of the device is as follows: Changes in the voltage of the circuit 2-3 cause a change in the setting of the relay 7 and, therefore, a change in the position of the lever 12. Changing the position of the lever 12 in the one direction or the other increases or decreases the tension on the spring 21, so that it becomes greater than or less than the tension on the spring 22, thus actuating the lever 18 in the one direction or the

other. Should slight changes in the setting of the lever 12 be maintained for only a short period, the contact members 14 or 15 would fail to make contact with the contact member 16 or 17, due to the space between the contact members. Should this changed setting of the relay be maintained, however, the lever 18 would gradually move to a position of rest such that the tension on the springs 21 and 22 would be equal, and thus effect engagement between contact members 14 and 16 or 15 and 17. The dashpot 24 acts to retard the motion of the lever 18 and the contact members 16 and 17 whereby, for slight changes in the line voltage that are maintained for only a short time, no correction by the induction regulator will be effected.

Should a large change in the voltage of the line occur, the degree of change in the position of the lever 12 and the contacts 14 and 15 would be sufficient to cause engagement of one of these contact members immediately. That is, the motion of the contact members 14 or 15 would be sufficient to bridge the space causing engagement with contact members 16 or 17 without the latter being moved to a new position.

While I have described my contact-making voltmeter as applied to the control of an induction regulator, it is obvious that it may be used to control any form of regulator, and it may be connected to be sensitive to current changes, or to any other electrical quantity, as well as to be sensitive to voltage changes.

Many modifications within the spirit and scope of my invention will occur to those skilled in the art and I do not wish to be limited other than by the scope of the appended claims.

I claim as my invention:

1. In a regulator, an electromagnet energized in accordance with the quantity to be regulated, a pair of contact members actu-

ated by said electromagnet, a second pair of contact members co-operating with the first-named contact members, and resilient means for actuating said second pair of contact members, means for varying the bias of said resilient means in accordance with a change in the position of said first pair of contact members.

2. In a regulator, an electromagnet energized in accordance with the quantity to be regulated, a pair of contact members actuated by said magnet, a second pair of contact members co-operating with the first-named contact members, and resilient means connected between said pairs of contact members for actuating said second pair of contact members in accordance with variations in the position of said first-named contact members.

3. In a contact making relay, an electromagnet, a pair of contact members operated by said electromagnet, a pair of auxiliary contact members co-operating with said first-named contact members, a resilient connection between said electromagnet and said auxiliary contact members for actuating said auxiliary contact members, and means for retarding the action of said auxiliary contact members.

4. In a contact making relay, a pair of contact members, a lever for supporting said contact members, an electromagnet operatively connected to said lever, a pair of auxiliary contact members and a lever for supporting said auxiliary contact members, a resilient connection between said levers for actuating said auxiliary contact members, and means for retarding the action of said auxiliary contact members after the actuation of said first-named contact members.

In testimony whereof, I have hereunto subscribed my name this 3rd day of September, 1924.

EDWIN LEHR.
